(57) **CLAIM**

The ornamental design for a lighting device, as shown and described.

DESCRIPTION

FIG. 1 is an isometric front view of the light device.

FIG. 2 is a back view of the light device.

FIG. 3 is a front view of the light device.

FIG. 4 is a left view of the light device.

FIG. 5 is a right view of the light device.

FIG. 6 is a top view of the light device.

FIG. 7 is a bottom view of the light device.

FIG. 8 is an isometric back view of the light device.

FIG. 9 is an isometric front view of the light device with the arms retracted, shown with a camera in broken lines; and, FIG. 10 is an isometric front view of the light device with the arms extended, shown with a camera in broken lines. The broken lines seen in FIGS. 7 and 8 show portions of the article that form no part of the claimed design.

The broken line showing of the camera in FIGS. 9 and 10 is for the purpose illustrating environmental structure and forms no part of the claimed design.

1 Claim, 10 Drawing Sheets
